(57) **ABSTRACT**

A corbel mounting assembly can include a corbel mounting member having a concrete anchor arrangement and a planar corbel mounting surface. The planar corbel mounting surface can extend along a mounting plane. A beam securement member is also included, having a concrete anchor arrangement and a planar beam securement surface. The beam securement member can be rigidly secured to and spaced apart from the corbel mounting member by a connecting member. The planar corbel mounting surface and the planar beam securement surface can be aligned with each other along the mounting plane. The connecting member can have a connecting member surface extending along a connecting member surface plane that is spaced apart from and parallel to the mounting plane. The connecting member can extend interactively relative to the concrete anchor arrangements of the corbel mounting member and the beam securement member.

REINFORCEMENT APPARATUS FOR CONCRETE

BACKGROUND

Concrete structures such as concrete walls can be formed with embedded corbel mounting plates and weld plates. A corbel mounted on the corbel mounting plate can support the leg of a concrete double Tee beam, and the upper end of the leg can be welded to the weld plate, for securing in place. In the prior art, when the concrete walls are being manufactured in a wall casting form, the corbel mounting plates and the weld plates are set up in the wall casting form by separately tying each to rebar cages prior to pouring the concrete.

SUMMARY

The present disclosure includes a corbel mounting assembly for a concrete structure such as a concrete wall, that can be set up in a concrete structure or wall casting form more quickly than prior methods. In addition, when the finished concrete wall is installed on site, the corbel mounting assembly can more securely hold the leg of a concrete beam in place on a corbel that is mounted to the corbel mounting assembly. The corbel mounting assembly can include a corbel mounting member having a concrete anchor arrangement and a planar corbel mounting surface. The planar corbel mounting surface can extend along a mounting plane. A beam securement member is also included, having a concrete anchor arrangement and a planar beam securement surface. The beam securement member can be rigidly secured to and spaced apart from the corbel mounting member by a connecting member. The planar corbel mounting surface and the planar beam securement surface can be aligned with each other along the mounting plane. The connecting member can have a connecting member surface extending along a connecting member surface plane that is spaced apart from and parallel to the mounting plane. The connecting member can extend interactively relative to the concrete anchor arrangements of the corbel mounting member and the beam securement member.

In particular embodiments, the corbel mounting member and the beam securement member can be each formed of planar steel plates. The concrete anchor arrangements of the corbel mounting member and the beam securement member can each include at least two elongate anchor members rigidly extending from respective corbel mounting and beam securement members in a direction opposite to the mounting plane. The connecting member can include two parallel elongate steel bars rigidly secured to respective anchor members on the corbel mounting member and the beam securement member. The connecting member surface of the two steel bars can extend along the connecting member surface plane spaced apart from the mounting plane by at least 1½ inches. In some embodiments, the corbel mounting member can be about 15 to 18 inches wide by 12 to 14 inches high and ½ inch thick. The beam securement member can be about 7 to 10 inches wide by 2 to 4 inches high and ½ inch thick. The elongate steel bars can be about ½ inch in diameter, and the height of the corbel mounting assembly can be about 27 to 48 inches high. A corbel can be included and mounted to the planar corbel mounting surface. The corbel mounting assembly can be embedded in a concrete wall and can be part of a beam mounting assembly. The planar corbel mounting surface and the planar beam securement surface can extend along an exterior surface of the

concrete wall. An upper surface of the corbel can support a bottom of a beam, and the planar beam securement surface can be rigidly secured to an end of the beam, thereby rigidly holding the beam on the upper surface of the corbel with a rigid connection of the beam securement member to the corbel mounting member by the connecting member.

The present disclosure can also provide a corbel mounting assembly including a corbel mounting plate having at least two concrete anchor members and a planar corbel mounting surface. The planar corbel mounting surface can extend along a mounting plane. A beam securement plate can be included having at least two concrete anchors and a planar beam securement surface. The beam securement plate can be rigidly secured to and spaced apart from the corbel mounting plate by a connecting member having two parallel elongate bars rigidly secured to respective anchor members on the corbel mounting plate and the beam securement plate. The planar corbel mounting surface and the planar beam securement surface can be aligned with each other along the mounting plane. The two parallel elongate bars of the connecting member can have a connecting member surface extending along a connecting member surface plane that is spaced apart from and parallel to the mounting plane.

The present disclosure can also provide a method of forming a corbel mounting assembly for a concrete structure, that includes providing a corbel mounting member having a concrete anchor arrangement and a planar corbel mounting surface. The planar corbel mounting surface can extend along a mounting plane. A beam securement member can be rigidly secured to the corbel mounting member in a spaced apart manner with a connecting member. The beam securement member can have a concrete anchor arrangement and a planar beam securement surface. The planar corbel mounting surface and the planar beam securement surface can be aligned with each other along the mounting plane. The connecting member can have a connecting member surface extending along a connecting member surface plane that is spaced apart from and parallel to the mounting plane. The connecting member can extend interactively relative to the concrete anchor arrangements of the corbel mounting member and the beam securement member.

In particular embodiments, the corbel mounting member and the beam securement member can each be formed of planar steel plates. The concrete anchor arrangements of the corbel mounting member and the beam securement member can be each provided with at least two elongate anchor members rigidly extending from respective corbel mounting and beam securement members in a direction opposite to the mounting plane. The connecting member can be provided with two parallel elongate steel bars rigidly secured to respective anchor members on the corbel mounting member and the beam securement member. The connecting member surface of the two steel bars can extend along the connecting member surface plane spaced apart from the mounting plane by at least 1½ inches. In some embodiments, the corbel mounting member can be about 15 to 18 inches wide by 12 to 14 inches high and ½ inch thick. The beam securement member can be about 7 to 10 inches wide by 2 to 4 inches high and ½ inch thick. The elongate steel bars can be about ½ inch in diameter, and the height of the corbel mounting assembly can be about 27 to 48 inches high. A corbel can be mounted to the planar corbel mounting member. The corbel mounting assembly can be embedded in a concrete wall. The planar corbel mounting surface and the planar beam securement surface can extend along an exterior surface of the concrete wall. The corbel mounting assembly can be part of a beam mounting assembly where a bottom of a beam can

be supported with an upper surface of the corbel. An end of the beam can be rigidly secured to the beam securement surface, thereby rigidly holding the beam on the upper surface of the corbel with rigid connection of the beam securement member to the corbel mounting member by the connecting member.

BRIEF DESCRIPTION OF THE DRAWINGS

The foregoing will be apparent from the following more particular description of example embodiments, as illustrated in the accompanying drawings in which like reference characters refer to the same parts throughout the different views. The drawings are not necessarily to scale, emphasis instead being placed upon illustrating embodiments.

FIG. 1 is a side schematic drawing of an embodiment of a concrete wall having a corbel mounting assembly supporting a double Tee beam in the present disclosure, and also forming a beam mounting assembly.

FIG. 2 is a front view of a portion of a concrete wall with a corbel mounting assembly.

FIG. 3 is an end view of a double Tee beam.

FIG. 4 is a perspective view of an embodiment of a corbel mounting assembly.

FIG. 5 is a front view of an embodiment of a corbel mounting assembly.

FIG. 6 is a rear view thereof.

FIG. 7 is a side view thereof.

FIG. 8 is an end view thereof.

FIGS. 9 and 10 are schematic drawings depicting tension forces on a connecting member of a corbel mounting assembly in response to an upward force on a double Tee beam.

FIG. 11 is a side schematic drawing of a portion of a concrete wall being formed in a concrete wall casting form, incorporating an embodiment of a corbel mounting assembly.

FIG. 12 is a side view of another embodiment of a corbel mounting assembly supporting a double Tee beam.

FIG. 13 is a side view of still another embodiment of a corbel mounting assembly supporting a double Tee beam.

DETAILED DESCRIPTION

A description of example embodiments follows.

Referring to FIG. 1, in the present disclosure, a concrete structure such as a concrete wall 22 can have an embodiment of a corbel mounting assembly 10 embedded, formed or cast into the concrete wall 22. The corbel mounting assembly 10 can interact with front and rear rebar cages 34 and 36. The corbel mounting assembly 10 can include a corbel mounting member or plate 12 and a beam securement member or weld plate 18. A corbel 20 (FIG. 2) can be secured to the corbel mounting plate 12. A top or upper surface 20c of the corbel 20 supports the bottom surface 24d of a stem or leg 24a of a concrete double Tee beam 24. The ends 24c of the double Tee beam 24 can include an embedded metal securement or weld plate 26 on the upper flange region 24b of the double Tee beam 24 aligned with and above each leg 24a (FIG. 3). The metal plate 26 at the end 24c of the double Tee beam 24 can be rigidly secured to the beam securement plate 18, such as by welding a weld bead 28, to rigidly secure the double Tee beam 24 to the corbel mounting assembly 10 and the concrete wall 22. This can also form a beam mounting assembly. As shown in FIG. 3, a double Tee beam 24 typically has two downwardly extending legs 24a, so that a single double Tee beam 24 is supported by two corbel

mounting assemblies 10 and associated mounted corbels 20, and is also welded to or against two beam securement plates 18.

Referring to FIGS. 4-8, embodiments of the corbel mounting assembly 10 can include a planar steel corbel mounting member or plate 12 having a planar first, front or corbel mounting surface 12a for being generally flush or at the level of a front, exterior or outer surface 22a of a concrete structure or wall 22. The corbel mounting surface 12a can extend along a front, mounting or wall face plane P₁. The mounting plane P₁ can lie on an XY axes plane. A planar second, back or rear surface 12b can include a first or lower concrete anchor arrangement extending from surface 12b in a perpendicular manner rearwardly in a direction opposite to the mounting plane P₁. The anchor arrangement can have 8 anchor members, bars or rods 16 each with a head 16a, welded to and extending perpendicular from the surface 12b of corbel mounting plate 12 rearwardly in a Z axis direction opposite to the mounting plane P₁. The anchor rods 16 can be in two rows of four, such as near the top and bottom regions. The corbel mounting plate 12 can include a pair of elongate vertical slots 13a positioned above and in line with a pair of smaller slots or openings 13b (FIG. 5), for accepting respective locking members or flanges 20a and 20b of a corbel 20 (FIG. 1) for mounting corbel 20 to the corbel mounting plate 12. The locking flanges 20a and 20b can extend rearwardly from the corbel 20 to lock the corbel 20 in place on the corbel mounting surface 12. In some embodiments, other suitable slot and locking member arrangements or configurations can be used. Additionally, in other embodiments, the corbel 20 can be mounted, secured or locked to the corbel mounting plate 12 by other suitable methods such as by welding or by bolts.

The corbel mounting plate 12 can be rigidly connected to a planar steel beam securement member or plate 18 by an elongate connecting member which can include two parallel elongate steel connecting bars or rods 14 such as rebar, extending along two respective parallel axes A, in the Y axis direction. The beam securement plate 18 can have a planar first, front or beam securement surface 18a for being generally flush or at the level of surface 22a of concrete wall 22. A planar second, back or rear surface 18b can include a second or upper concrete anchor arrangement extending from surface 18b in a perpendicular manner rearwardly in a direction opposite to the mounting plane P₁. The anchor arrangement can have three anchor members, bars or rods 16 each with a head 16a, welded to and extending perpendicular from surface 18b of beam securement plate 18 rearwardly in a Z axis direction opposite to the mounting plane P₁, and can be in a single central row.

The planar corbel mounting surface 12a and the planar beam securement surface 18a can be oriented or aligned with each other along the mounting plane P₁, allowing both surfaces 12a and 18a to be formed in a concrete structure or wall 22, and be flush with or at the same level as a front, exterior or outer surface 22a. The two steel connecting rods 14 can be rigidly secured to four anchor rods 16 of the corbel mounting plate 12, two at the top and two at the bottom, such as by welding on the outer sides of the anchor rods 16, and can be rigidly secured to two anchor rods 16 of the beam securement plate 18, such as by welding on the inner sides of the anchor rods 16. Securement of the connecting rods 14 to the anchor rods 16 allows the connecting rods 14 to be positioned a desired distance d away from the mounting plane P₁. For example, the front surfaces 14a of the connecting rods 14 can be aligned parallel to each other along a connecting member surface plane P₂ that is spaced rear-

wardly apart from and parallel to the mounting plane P_1 by distance d of $1\frac{1}{2}$ inches or at least $1\frac{1}{2}$ inches in the Z axis direction. The connecting member surface plane P_2 can lie along an XY axes plane. This can position the connecting rods **14** at least $1\frac{1}{2}$ inches rearwardly under the surface **22a** of concrete wall **22**, for better securement within concrete wall **22** and better strength.

The dimensions of the corbel mounting assembly **10** can vary depending upon the size of the double Tee beam **24** that is being supported. In some embodiments, the height of the corbel mounting assembly **10** can be about 27 to 48 inches high and in one embodiment about $29\frac{1}{2}$ inches high. The corbel mounting plate **12** can be about 15 to 18 inches wide by about 12 to 14 inches high and about $\frac{1}{2}$ inch thick, and in one embodiment, can be $15\frac{1}{2}$ inches wide by 12 inches high. The anchor rods **16** on the corbel mounting plate **12** can have a round cross section with about a $\frac{3}{4}$ inch diameter with a $1\frac{1}{4}$ diameter head **16a**, and can be about $8\frac{1}{2}$ inches long. Each row of anchor rods **16** can space the anchor rods **16** on the corbel mounting plate **12** about $4\frac{1}{2}$ inches apart, and the two rows at the top and bottom regions can be about 10 inches apart. The connecting rods **14** can have a round cross section and can be about $\frac{1}{2}$ inch in diameter and can space the center of the beam securement plate **18** from the top of the corbel mounting plate **12** about 16 inches in one embodiment, and in other embodiments can be spaced about 15 to 28 inches. The beam securement plate **18** can be about 7 to 10 inches wide by 2 to 4 inches high, and $\frac{1}{2}$ inch thick, and in one embodiment, can be $7\frac{1}{8}$ inches wide and $2\frac{7}{8}$ inches high. Three anchor rods **16** can extend from beam securement plate **18** and can be about 6 to 7 inches long. In some embodiments, components of a Rapid-Lok™ corbel arrangement can be incorporated into corbel mounting assembly **10**, such as on the corbel mounting plate **12**.

Referring to FIGS. 1, 9 and 10, by rigidly securing beam securement plate **18** to the corbel mounting plate **12** with connecting rods **14**, the double Tee beam **24** that is supported by corbel **12**, can be more securely held in place once beam securement plate **18** is welded to the plate **26** on the end **24c** of the double Tee beam **24**. For example, if external forces such as an earthquake or a vehicle driving over the double Tee beam **24** causes an upward force U on the double Tee beam **24**, the connecting rods **14** that rigidly secure the beam securement plate **18** to the corbel mounting plate **12** can resist the upward force U with opposite tension force T along the parallel axes A to keep the double Tee beam **24** held tight in position on the top surface **20c** of the corbel **20**. This can provide resistance to upward forces U even if portions of the concrete wall **22** between the beam securement plate **18** and the corbel mounting plate **12** deteriorate over time. Rigid securement connecting the following components together in series, the plate **26** on the end **24c** of the double Tee beam **24**, the beam securement plate **18**, the anchor rods **16** extending from the beam securement plate **18**, the connecting rods **14**, the anchor rods **16** extending from the corbel mounting plate **12**, and the corbel mounting plate **12**, lock the double Tee beam **24** in place over the top surface **20c** of the corbel **20**, once the double Tee beam **24** is welded to the beam securement plate **18** by weld **28**. Upward force U of the double Tee beam **24** is directed on the beam securement plate **18** along mounting plane P_1 but is resisted by the tension force T on the connecting rods **14** along axes A rearwardly offset from the mounting plane P_1 by distance d_a . The connecting rods **14** rigidly secure the beam securement plate **18** to the corbel mounting plate **12** and associated anchor rods **16**, and can provide greater resistance to the upward force U . Rigidly securing two

spaced apart connecting rods **14** to anchor rods **16** at the top and bottom of the corbel mounting plate **12** can more evenly spread out the forces transmitted by the connecting rods **14** over the corbel mounting plate **12** for better force absorption.

In addition, under normal conditions, the weight of the double Tee beam **24** exerts a load or force F from each leg **24a** generally onto a corbel **20** and corbel mounting plate **12**, and then onto the concrete wall **22**. The load F can also exert a moment M on the corbel mounting plate **12** about pivot point O at the bottom front edge of the mounting plate **12**. With the corbel mounting plate **12** being rigidly secured to the beam securement plate **18** by the connecting rods **14** above the corbel mounting plate **12**, both the downward force F and the moment M about pivot point O can be resisted by both the anchor rods **16** of the corbel mounting plate **12**, and the anchor rods **16** of the beam securement plate **18**, thereby providing increased strength for supporting the double Tee beam **24**. In addition, the connecting rods **14** can also provide resistance against the moment about pivot point O since the connecting rods **14** are embedded in the concrete **30**.

Referring to FIG. 11, corbel mounting assembly **10** is shown being formed into a concrete structure such as a wall **22**. Two layers of rebar cages, front cage **34** and rear cage **36** can be positioned within the concrete structure or wall casting form **32**. The corbel mounting assembly **10** is positioned in place and fastened to front cage **34** with fasteners **38** such as wire. Temporary removable plugs can be inserted into slots **13a** and **13b** in the corbel mounting plate **12** to prevent the slots **13a** and **13b** from being filled with concrete. Concrete **30** is poured into the wall casting form **32** with the surface **30a** of the concrete **30** being level with the mounting plane P_1 of the corbel mounting assembly **10**. As a result, the surface **30a** of the concrete **30** can be flush with the front surfaces **12a** and **18a** of corbel mounting plate **12** and beam securement plate **18**, at a distance d such as $1\frac{1}{2}$ inches above connecting member surface plane P_2 and the front surfaces **14a** of the connecting rods **14**. The surface **30a** of the concrete **30** when cured, forms the front outer surface **22a** of concrete wall **22**. By having the beam securement plate **18** rigidly secured to the corbel mounting plate **12** prior to pouring the concrete **30**, the spacing and alignment in the X, Y and Z axes between the plates **18** and **12** can be controllably preset prior to insertion into the wall casting form **32**. This increases the speed at which the corbel mounting plate **12** and beam securement plate **18** can be set up in the wall casting form **32** and eliminates the need for external positioning jigs above the wall form **32**, which also makes smoothing or spreading out the surface **30a** of the poured concrete **30** faster and easier. The corbel mounting assembly **10** can allow a concrete wall **22** to be poured in about half the time than the prior art methods. Furthermore, by having the corbel mounting plate **12** and beam securement plate **18** aligned relative to each other in the X, Y and Z axes, the plates **26** of each double Tee beam **24** can be welded to each beam securement plate **18** with consistent repeatable characteristics, improving quality control.

Referring to FIGS. 12 and 13, the distance or spacing of the center of the beam securement plate **18** from the top of the corbel mounting plate **12** of the corbel mounting assembly **10** can vary, and some embodiments can have spacings of $16\frac{1}{4}$ inches (about 16 inches), 19 inches, 20 inches, $24\frac{3}{4}$ inches (about 24 inches), $27\frac{1}{2}$ inches (about 27 inches), and $28\frac{1}{2}$ inches (about 28 inches). FIGS. 12 and 13 show spacings of $24\frac{3}{4}$ inches and 19 inches, respectively. Some embodiments of the corbel mounting assembly **10** can

include two lateral rows of anchor rods 16 extending from the upper half or portion of the corbel mounting plate 12 (FIG. 12), and other embodiments can include three lateral rows of anchor rods 16 extending from the top, middle and bottom portions of the corbel mounting plate 12 (FIG. 13). The bottom surface 24d of the double Tee beam 24 can include a metal or steel plate 25 that can be supported by the upper surface 20c of the corbel 20 with a pad, or can be welded to the upper surface 20c. In some embodiments, the double Tee beam 24 can have a recess, step or notch 27 with an elevated or recessed bottom surface 24d that is supported by the corbel 20. In some embodiments, the plate 26 on the end 24c of the double Tee beam 24 can have the upper edge slightly angled away from the beam securement plate 18 to facilitate welding to the beam securement plate 18.

While example embodiments have been particularly shown and described, it will be understood by those skilled in the art that various changes in form and details may be made therein without departing from the scope of the embodiments encompassed by the appended claims.

For example, in embodiments of the corbel mounting assembly 10, the dimensions of the different components can vary depending upon the situation at hand, and the size of the double Tee beam to be supported. Although terms such as front, rear, rearwardly, top, bottom, wide, high, etc. have been used, it is understood that such terms can differ depending upon the spatial orientation of the corbel mounting assembly 10. Furthermore, the connecting member can be a single member or include multiple members such as more than two connecting members or rods 14. In addition to the connecting rods 14 and anchor rods 16 having a round cross section, the connecting rods 14 and anchor rods 16 can have other suitable cross sections such as rectangular, polygonal or oval etc. The configuration, number, size and placement of the anchor members can also vary. The corbel mounting assembly 10 can also be used in other concrete structures, such as in columns. Features of different embodiments shown and/or described can be combined together or omitted.

What is claimed is:

1. A corbel mounting assembly for a concrete structure comprising:

a corbel mounting member having a concrete anchor arrangement and a planar corbel mounting surface, the planar corbel mounting surface extending along a mounting plane; and

a beam securement member having a concrete anchor arrangement and a planar beam securement surface, the beam securement member being rigidly secured to and spaced apart from the corbel mounting member by a connecting member, the planar corbel mounting surface and the planar beam securement surface being aligned with each other along the mounting plane, the connecting member having a connecting member surface extending along a connecting member surface plane that is spaced apart from and parallel to the mounting plane, the connecting member extending interactively relative to the concrete anchor arrangements of the corbel mounting member and the beam securement member, each of the concrete anchor arrangements extending from respective corbel mounting and beam securement members in a direction opposite to the mounting plane.

2. The corbel mounting assembly of claim 1 in which the corbel mounting member and the beam securement member are each formed of planar steel plates.

3. The corbel mounting assembly of claim 2 in which the concrete anchor arrangements of the corbel mounting member and the beam securement member each comprise at least two elongate anchor members rigidly extending from respective corbel mounting and beam securement members in the direction opposite to the mounting plane.

4. The corbel mounting assembly of claim 3 in which the connecting member comprises two parallel elongate steel bars rigidly secured to respective anchor members on the corbel mounting member and the beam securement member, the connecting member surface of the two steel bars extending along the connecting member surface plane spaced apart from the mounting plane about 1½ inches.

5. The corbel mounting assembly of claim 4 in which the corbel mounting member is about 15 to 18 inches wide by 12 to 14 inches high and ½ inch thick, the beam securement member is about 7 to 10 inches wide by 2 to 4 inches high and ½ inch thick, the elongate steel bars are about ½ inch in diameter, and a height of the corbel mounting assembly is about 27 to 48 inches high.

6. The corbel mounting assembly of claim 4 in which a corbel is mounted to the planar corbel mounting surface.

7. The corbel mounting assembly of claim 6 in which the corbel mounting assembly is embedded in a concrete wall and is part of a beam mounting assembly, the planar corbel mounting surface and the planar beam securement surface extending along an exterior surface of the concrete wall, an upper surface of the corbel supporting a bottom of a beam, the planar beam securement surface being rigidly secured to an end of the beam, thereby rigidly holding the beam on the upper surface of the corbel with rigid connection of the beam securement member to the corbel mounting member by the connecting member.

8. A corbel mounting assembly comprising:
a corbel mounting plate having at least two concrete anchor members and a planar corbel mounting surface, the planar corbel mounting surface extending along a mounting plane; and

a beam securement plate having at least two concrete anchor members and a planar beam securement surface, the beam securement plate being rigidly secured to and spaced apart from the corbel mounting plate by a connecting member having two parallel elongate bars rigidly secured to respective anchor members on the corbel mounting plate and the beam securement plate, the planar corbel mounting surface and a planar beam securement surface being aligned with each other along the mounting plane, the two parallel elongate bars of the connecting member having a connecting member surface plane that is spaced apart from and parallel to the mounting plane, each of the concrete anchor members extending from respective corbel mounting and beam securement plates in a direction opposite to the mounting plane.

9. A method of forming a corbel mounting assembly for a concrete structure comprising:

providing a corbel mounting member having a concrete anchor arrangement and a planar corbel mounting surface, the planar corbel mounting surface extending along a mounting plane; and

rigidly securing a beam securement member to the corbel mounting member in a spaced apart manner with a connecting member, the beam securement member having a concrete anchor arrangement and a planar beam securement surface, the planar corbel mounting surface and the planar beam securement surface being

aligned with each other along the mounting plane, the connecting member having a connecting member surface extending along a connecting member surface plane that is spaced apart from and parallel to the mounting plane, the connecting member extending interactively relative to the concrete anchor arrangements of the corbel mounting member and the beam securement member, each of the concrete anchor arrangements extending from respective corbel mounting and beam securement members in a direction opposite to the mounting plane.

10. The method of claim 9 in which the corbel mounting member and the beam securement member are each formed of planar steel plates.

11. The method of claim 10 further comprising providing the concrete anchor arrangements of the corbel mounting member and the beam securement member each with at least two elongate anchor members rigidly extending from respective corbel mounting and beam securement members in the direction opposite to the mounting plane.

12. The method of claim 11 further comprising providing the connecting member with two parallel elongate steel bars rigidly secured to respective anchor members on the corbel mounting member and the beam securement member, the connecting member surface of the two steel bars extending

along the connecting member surface plane spaced apart from the mounting plane about 1½ inches.

13. The method of claim 12 in which the corbel mounting member is about 15 to 18 inches wide by 12 to 14 inches high and ½ inch thick, the beam securement member is about 7 to 10 inches wide by 2 to 4 inches high and ½ inch thick, the elongate steel bars are about ½ inch in diameter, and a height of the corbel mounting assembly is about 27 to 48 inches high.

14. The method of claim 12 further comprising mounting a corbel to the planar corbel mounting member.

15. The method of claim 14 further comprising embedding the corbel mounting assembly in a concrete wall, the planar corbel mounting surface and the planar beam securement surface extending along an exterior surface of the concrete wall.

16. The method of claim 15 further comprising forming a beam mounting assembly comprising:

supporting a bottom of a beam with an upper surface of the corbel; and
rigidly securing an end of the beam to the planar beam securement surface, thereby rigidly holding the beam on the upper surface of the corbel with rigid connection to the beam securement member to the corbel mounting member by the connecting member.
